US00D898302S

(12) **United States Design Patent** (10) Patent No.: **US D898,302 S**
(45) Date of Patent: **** Oct. 6, 2020**

(54) **PET HAIR REMOVER**

(71) Applicant: **Weinan Zhang**, Yixing (CN)

(72) Inventor: **Weinan Zhang**, Yixing (CN)

(**) Term: **15 Years**

(21) Appl. No.: **29/735,736**

(22) Filed: **May 22, 2020**

(51) LOC (12) Cl. **30-99**

(52) U.S. Cl.

USPC **D30/159**

(58) **Field of Classification Search**

CLAIM

The ornamental design for a pet hair remover, as shown and described.

DESCRIPTION

FIG. 1 is a front perspective view of a pet hair remover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines are for environmental structure, boundaries, or illustrative purposes only and form no part of the claimed designs to be patented.

1 Claim, 7 Drawing Sheets
